[57] CLAIM

The ornamental design for a roach trap, as shown.

DESCRIPTION

FIG. 1 is a side view of a transparent bottom vessel component of the roach trap, without the roach capturing entry port mounted on its top.

FIG. 2 illustrates a bottom plan view of the bottom vessel component of FIG. 1.

FIG. 3 is a side view of the transparent bottom vessel component of FIG. 1, having its roach capturing entry port mounted on its top, showing a portion of that entry port structure extending downwardly into the inner space of the transparent bottom vessel as viewed through transparent walls of the bottom vessel component.

FIG. 4 illustrates a top plan view of the entry port structure in its mounted state of FIG. 3.
